UNITED STATES PATENT OFFICE.

JOHN M. O'GRADY, OF CHICAGO, ILLINOIS.

ROTARY MOTOR.

1,270,546.

Specification of Letters Patent. Patented June 25, 1918.

Application filed July 30, 1915. Serial No. 42,679

To all whom it may concern:

Be it known that I, JOHN M. O'GRADY, a citizen of the United States, residing at Chicago, in the county of Cook and State 5 of Illinois, have invented new and useful Improvements in Rotary Motors, of which the following is a specification, reference being had to the accompanying drawings, forming a part thereof.

10 This invention relates to a rotary engine and is concerned chiefly with features which are equally valuable whether the motive fluid be steam or an explosive mixture. The invention is concerned especially with features designed to secure a simplicity of construction and quietness in operation, such features being hereinafter described and illustrated in the drawings and more particularly defined in the appended claims.

15 20 In the drawings:

Figure 1 is a sectional view taken in a plane perpendicular to the shaft axis and illustrating a motor embodying this invention.

25 Fig. 2 is an axial section taken as indicated at line 2—2 on Fig. 1.

Fig. 3 is an exterior view of the motor showing one end wall.

30 Fig. 4 is a detail section taken as indicated at line 4—4 on Fig. 3.

Fig. 5 is a detail section of the rotor showing the intake ports, section being taken at a plane between the face of the rotor into which the ports are cut and the 35 face of the stationary valve member through which the gas supply comes.

Fig. 6 is a detail section taken as indicated at line 6—6 on Fig. 2.

The motor illustrated in the drawings 40 comprises a stationary casing, 1, having two similar and symmetrically arranged expansion chambers, 1^a, whose peripheral walls are connected by substantially, cylindrically curved portions, 1^b, between which 45 there is snugly fitted a cylindrical rotor, 2. This rotor is formed as a barrel having a central web portion, 2^a, located mid-way between its ends and extending to a hub, 2^b, which is fixed on a shaft, 3, journaled at 1^c, 50 in the end walls of the casing, 1.

The particular motor illustrated is intended for use as an internal combustion engine, it being expected however that the explosive mixture will be furnished to the 55 motor under pressure, hence the motor itself has no provision for compressing the

gas previously to exploding it. Such gas is admitted through an intake pipe, 4, communicating with an aperture, 5^a, in an annular valve member, 5, seated in a groove, 2^c, 60 in the rotor, 2.

The cylindrical wall of the rotor, 2, is formed with a series of recesses, 2^d, and associated grooves, 2^e, said grooves being a little more than semicircular in cross section. The cylindrically formed base, 6^a, of piston member, 6, being inserted in one of these grooves, 2^e, forms with it a kind of hinged connection between the member, 6, and the rotor, 2, the former being locked 70 in the latter by reason of the overhanging form of the circular groove, 2^e. One such gate or piston is hinged in each of the grooves 2^e, and arranged to be accommodated at the recess, 2^d, when folded down 75 against the rotor, 2, in which position the back surface, 6^b, of the piston member, 6, is cylindrically curved to form a continuation of the cylindrical surface of the rotor, 2.

80 Leading from each of the recesses, 2^d, there is formed in the web portion, 2^a, of the rotor, 2, a passage, 2^f, which terminates in an aperture opposite the valve member, 5, as indicated in Fig. 2. Such aperture may 85 be somewhat elongated by a recess in the face of the groove, 2^e, extended a little at 2^g, in the path of rotation of the mouth of the passage, 2^f. Now as the rotor, 2, revolves in the direction of the arrow, X, on 90 Fig. 1, the mouths of the passages, 2^f, will pass successively into registration with the port, 5^a, of the valve member, 5, letting the compressed gas from the pipe, 4, into the passages, 2^f. This registration is designed 95 to occur just before the free end of the piston or gate, 6, escapes from the circular portion, 1^b, of the casing wall, and such registration should continue a little after the said free end of the piston member has 100 passed such point. The centrifugal force acting on the hinged piston, 6, as well as the pressure of the gas confined in the passages, 2^f, will operate to throw the piston open with its outer edge against the wall of the 105 expansion chamber, 1^a. As the piston passes the recess in which the spark plug, 7, is positioned, the extended mouth, 2^g, will pass the aperture, 5^a, of the valve member, 5, closing off the passage, 2^f, and then by any 110 suitable means associated with the rotor but not shown in the drawings, the spark

plug, 7, may be energized to ignite the mixture thus pocketed in the passage, 2^c, and around the plug, 7. The explosion of the mixture will then drive the piston member, 6, through the expansion chamber, 1^a, and past the exhaust port, 8, from which the burnt gases will then escape.

It should be noted that as the piston, 6, approaches the final straight portion, 1^d, of the wall of the expansion chamber, 1^a, it is disposed at a slight angle to said wall so that it tends to pocket a little air or gas which will operate as a cushion, preventing any noisy contact between the piston and the wall. Likewise the recess, 2^d, into which the piston eventually folds is a sufficiently snug fit to provide a slight air cushion as the piston folds into place, thus eliminating noise at this point also.

20 For holding the valve member, 5, firmly on to its seat in the groove, 2^c, there is provided an adjustable pressure member, 8^b, having a foot, 8^a, attached as by screws, 8^b, to the valve member, 5, and having a cylindrically curved web, 8^c, terminating in a flange, 8^d, adjacent to the end wall of the casing, 1. Threaded studs, 8^e, are slidably mounted in the casing wall, and additionally guided in a bracket, 9, carried thereon; springs, 8^f, reacting against said bracket, 9, and adjustable nuts, 8^g, on the studs, 8^e, yieldingly force said studs against the pressure member, 8^b, through which said yielding pressure is transmitted to the valve member, 5. The studs, 8^e, engage recesses in the flange, 8^d, of the pressure member to restrain the latter and its connected valve member, 5, against rotation. It will be understood that two gas inlet pipes, 4, are provided corresponding with the two expansion chambers, 1^a, and that likewise two pressure members, 8^b, are arranged to occupy the angular space between said inlet pipes, 4. To take up the yielding pressure of the valve member, 5, against its seat on the rotor there is provided an annular thrust bearing, 2^m.

To render the expansion chambers as nearly gas-tight as possible the cylindrical walls, 1^b, of the casing, 1, are provided with 50 packing strips, 10, extending parallel to the shaft axis in position for contact with the rotor as it revolves. The end walls of the expansion chamber, 1^a, are formed of packing plates, 11, yieldingly held in contact with the end surfaces of the rotor by yielding and adjustable devices similar to those provided for the valve member, 5. Springs, 12, react against the bracket, 9, and adjustable nuts, 13^a, on studs, 13, whose inner ends 60 abut the packing plates, 11, and transmit the yielding pressure of the springs, 12, thereto. To render the packing of the water

jacket wall, 2^k, independent of the plates, 11, said plates are recessed to accommodate packing rings, 14, which are yieldingly forced into place by springs, 15, reacting against the bracket, 9, and adjusting nuts, 16^a, on studs 16. It may be noted that each of the studs, 8^e, 13 and 16, is provided with lock nuts in addition to the adjusting nuts, 70 and that as indicated in Fig. 3 the ends of the studs are flattened to engage in non-circular openings in the bracket, 9, to facilitate adjustment of the nut.

The water jacket formed by the wall, 2^k, 75 communicates with hollow annular chambers, 11^a, in the packing plates, 11, which as indicated in Fig. 2 are connected in the water circulating system by inlet and outlet pipes, 17; similar pipes, 18, serve the annular water chamber, 19, of the peripheral casting wall.

I claim:

1. In a rotary motor comprising a cylindrical rotor, a piston hinged thereto and 85 adapted to fold into the cylindrical surface of said rotor, a stationary casing having a partially cylindrical wall with an outwardly bulging portion forming an expansion chamber, said piston being dimensioned to fold 90 out from the rotor for contact with said bulging wall, an adjustable end wall extending in a plane perpendicular to the axis of rotation, and formed to fit the outline of said stationary casing, and means for adjusting said wall in the direction of said axis of rotation against the end of the rotor and its piston.

2. In a rotary motor comprising a cylindrical rotor, a piston hinged thereto and 100 adapted to fold into the cylindrical surface of said rotor, a stationary casing having a partially cylindrical wall with an outwardly bulging portion forming an expansion chamber, said piston being dimensioned to fold 105 out from the rotor for contact with said bulging wall, said rotor having an annular wall within its outer cylindrical wall and spaced therefrom to form a chamber for cooling fluid, the end wall of the casing 110 having an annular flange positioned to register with said annular wall for closure of the cooling chamber, and conduits leading through said casing in registration with said chamber of the rotor to permit circulation of cooling fluid therethrough.

In testimony whereof I have hereunto set my hand at Chicago, Illinois, this 22nd day of July, 1915.

JOHN M. O'GRADY.
